UNITED STATES PATENT OFFICE.

CHARLES E. SAYRE, OF ST. PAUL, MINNESOTA.

CARBURETER.

SPECIFICATION forming part of Letters Patent No. 746,173, dated December 8, 1903.

Application filed January 2, 1903. Serial No. 137,487. (No model.)

To all whom it may concern:

Be it known that I, CHARLES E. SAYRE, a citizen of the United States of America, and a resident of St. Paul, in the county of Ramsey and State of Minnesota, have invented certain new and useful Improvements in Carbureters, of which the following is a specification.

My invention relates to improvements in carbureters, and has for its object to automatically control the supply of hydrocarbon to the various compartments of the device.

With this and other hereinafter-specified objects in view my invention consists of a receptacle divided into compartments, a suitable supply connection with said compartments, a valve in said connection, passage-ways between said compartments, and means governed by the quantity of hydrocarbon in said compartments for operating said valve.

My invention further consists of the features of construction and combination of parts hereinafter more particularly described and claimed.

In the accompanying drawings, forming part of this specification, Figure 1 is a transverse section of my improved carbureter, which is shown connected with a supply-tank. Fig. 2 is a plan view of Fig. 1, shown partly in section. Fig. 3 is a detail section of a portion of the carbureter, and Fig. 4 is a view of one of the frames for supporting the ends of the curtains in the carbureter.

In the drawings let A represent the carbureter, which is preferably inclosed by a cylindrical receptacle 2. This receptacle is divided into a plurality of superposed compartments 3, 4, 5, and 6. Although four compartments are herein illustrated, it will of course be understood that any suitable number may be employed. Each compartment is divided by curtains 7, 8, and 9 into a series of circular cells or passage-ways 10, 11, and 12. These curtains are preferably constructed of absorbent material, such as lamp-wick, which readily absorbs the hydrocarbon oil and diffuses the oil with air passing through the compartments. The partition 7 hangs lower in each compartment than do the curtains 8 or 9, so as to prevent the carbureted air short-circuiting between the cells when the device is in operation. The curtain 7 starts at the outer wall 2, nearly completes a

circle, and then swerves inward at 7' to an extent about equal to the space between the outer wall 2 and the curtain 7, the curtain then making a series of similar circuits which gradually grow smaller and open into the central chamber 15. The curtains 8 and 9 divide the passage-way thus formed into cells, which traverse its length and also open into the central chamber 15.

Each compartment 3, 4, 5, and 6 is divided from the next superposed compartment by means of floors 16, 16', and 16''. A series of curtains hang in each compartment and form a series of cells similar in construction to those in compartment 3. A wire frame 49, as shown in Fig. 4, may be used at the ends of the passage-ways of the compartments for holding the curtains in position. Compartment 3 is connected with compartment 4 by means of the overflow passage-way B. This passage-way is a tube 17, which is attached at 18 to the floor 16 of compartment 3 and projects above the surface of the hydrocarbon oil in said compartment. A branch tube 19 depends from the tube 17 into the oil and has connection with the main tube at 20, so that the heavy oil overflows from near the bottom of compartment 3 into compartment 4. The inner surface 21 of each compartment is covered with absorbent material 22 such as used for the curtains. The curtains are suitably attached to the covering 22, as by sewing. Said covering may be cemented or riveted to the inner surfaces of the receptacle. The floors of the respective compartments are strengthened by means of the posts 30. Compartment 4 has communication with compartment 5 by means of the overflow passage-way 23 and compartment 5 with compartment 6 by means of the overflow passage-way 24. The overflow passage-ways are all similar in construction. The overflow passage-way 23 is positioned near the outer wall 2 in compartment 4 and has communication through the opening 27 with compartment 5. The overflow passage-way 24 is positioned near the center of compartment 5 and has communication through the opening 28 with compartment 6. A compressed-air-supply tube 31 connects with the cells 10, 11, and 12 in compartment 6, and an outlet-tube 32 for the carbureted air is connected with compart-

ment 3, as shown in Fig. 1. Air entering through the inlet 31 circulates through the cells in the lower compartment and passes up through the tube 24 into compartment 5. After 5 circulating through the cells of compartment 5 it passes through the tube 23 into compartment 4. After circulating through the cells in compartment 4 it passes through the tube 17 into compartment 3, and after circulating 10 through the cells of compartment 3 passes out of the carbureter through the tube 32, which may lead to the mixing-chamber (not shown) of any suitable burner. A pipe 33 connects the top of the receptacle with the top of any 15 suitable hydrocarbon-supply tank 34 to maintain an equilibrium of pressure in the tank and in the carbureter, as above described. A tube 35 from said supply-tank discharges into a trough 36, which delivers hydrocarbon 20 from said tank into compartment 3 through the perforation 36' in the wall 2 of the carbureter. Any suitable valve 37 is attached over the outlet of the pipe 35 and has its stem 38 connected with the controlling-rod 39. 25 This rod has its lower end secured to a float 40, arranged within the chamber 41. The chamber 41 is attached on the side 2 of the receptacle A and communicates at 42, as shown in Fig. 1, with the compartment 6 of the carbureter.

In supplying hydrocarbon oil to the carbureter the tank 34 is filled, and the float 40 being in its lower position retains the valve 37 open. The hydrocarbon oil in the supply- 35 tank 34 flows through the pipe 35 down trough 36 into compartment 3. The oil overflows through the siphon 19 into compartment 4 and on through the succeeding compartments and siphons until it reaches the desired level 40 in chamber 41 and closes the valve 37 by lifting the float 40. The action of supplying hydrocarbon oil to the carbureter is thus automatic. It will be noted that the overflow-tubes 19 in the various compartments con- 45 duct the heavier oil into the compartment next beneath the one from which the oil is being discharged, and hence eventually all of the heavy matter within the oil is deposited in the lowermost compartment. A suitable 50 tube 48 is connected with compartment 6 for drawing off the refuse and heavier substances which are not vaporized.

In operation air is introduced through pipe 31, whence it passes through the various cells 55 in the carbureter, as above described, and out through the tube 32. Air passing through the carbureter is thus exposed to a maximum surface of oil in the receptacle, thereby charging the air with the hydrocarbon vapors, so that the same will support combustion. The compartment 41 is provided with a plug 43, which is threaded at 44 into the shell 2. By removing this plug the valve mechanism 60 is readily accessible for cleaning or repairing.

55 Although I have specifically set forth the particulars of one embodiment of the present

invention, yet it will be obvious to those skilled in the art to which this invention relates that many changes may be made within the spirit thereof—such, for instance, as 70 the provision of rectilinear or spiral passage-ways instead of those described, the main object of the construction set forth being the arrangement of a passage-way divided into a series of cells which starts at or near the outer 75 surface of the containing-wall and turns within the same until it eventually ends near the center of the structure. It will be observed that such arrangement may be used in connection with a containing-receptacle 80 square or otherwise shaped in cross-section.

Having described my invention, what I claim as new, and desire to protect by Letters Patent, is—

1. A carbureter, comprising a series of 85 superposed compartments, curtains therein dividing the same into continuous passage-ways, which circulate from the outer wall of each compartment about the center thereof, absorbent partitions longitudinally disposed 90 between said curtains, means for introducing atmosphere at one end of said passage-way formed by said curtains, and discharging atmosphere at the other end thereof, a chamber 95 communicating with the lower compartment, a float arranged in said chamber, means for supplying hydrocarbon oil to the upper compartment, valve mechanism controlling said supply, and connections between said valve mechanism and said float.

100 2. A carbureter, comprising a plurality of superposed compartments, curtains of absorbent material hung in each compartment, and dividing the same into a general passage-way, which is continuous, and extends from the 105 outer wall of each compartment to near the center thereof, partitions of absorbent material dividing said passage-way into a plurality of longitudinal cells, between said curtains, means for introducing atmosphere into 110 and conducting it from said cells, means for supplying hydrocarbon oil to said compartments, and means controlled by the supply 115 within the lower compartment for governing said supply to the upper compartment.

120 3. A carbureter, comprising a plurality of superposed compartments, curtains therein dividing the same into continuous passage-ways, which circulate from the outer wall of each compartment about the center thereof, 120 absorbent partitions longitudinally disposed between said curtains, a tube communicating between one compartment and the next succeeding compartment, a branch tube extending down from the first-mentioned tube, an opening 125 near the floor of each compartment, means for supplying hydrocarbon oil to the upper compartment, and means for introducing atmosphere at one end of said passage-way formed by said curtains and discharging atmosphere at the other end thereof.

130 4. A carbureter, comprising a suitable com-

- partment, a curtain therein dividing the same into a continuous passage-way, which circulates from the outer wall of said compartment about the center thereof, absorbent partitions longitudinally disposed between said curtain, a vertical tube projecting up from the floor of said compartment, an overflow-tube connected with said vertical tube and depending into said compartment, an outlet for the carbureted air in said compartment, an inlet for receiving hydrocarbon oil into said compartment, a valve controlling said inlet, a chamber on the side of the compartment, a communication, near the bottom of the compartment, with said chamber, a float in said chamber, and a connection between said float and valve for controlling the supply of hydrocarbon oil in the compartment.
5. A carbureter, comprising a plurality of superposed compartments, curtains therein, which form a continuous passage-way circulating from the side of each compartment substantially to its center, absorbent partitions longitudinally disposed between said curtains, a plurality of main tubes arranged on the floors of the compartments, branch tubes on said main tubes, which open near the floors of the compartments, an inlet for introducing atmosphere at one end of said 25 passage-way formed by said curtains, an outlet for discharging atmosphere at the other end thereof, a second inlet for oil in the upper compartment, a valve for closing said second inlet, a chamber adjoining the lower compartment, a communication between the lower compartment and said chamber, a float in said chamber, and a connection between said float and valve, for the purposes specified.
6. A carbureter, comprising a plurality of superposed compartments, curtains of absorbent material in said compartments, which form a general passage-way, partitions dividing said passage-way into a plurality of longitudinal cells between said curtains, main 30 tubes which lead the atmosphere from one compartment to another, branch tubes on said main tubes, which permit the oil in each compartment to overflow into the contiguous compartment, means for introducing atmosphere into the lower compartment and conducting it from said cells, an oil-inlet in the upper compartment, a valve in said oil-inlet, a float by which the level of the oil in the

lower compartment controls said valve, and a connection between said float and valve. 55

7. A carbureter comprising a suitable inclosure, curtains of absorbent material hung in said inclosure and dividing the same into a general passage-way which is continuous and extends from the outer wall of said inclosure to the center thereof, partitions of absorbent material dividing said passage-way into a plurality of longitudinal cells between said curtains, and means for introducing atmosphere into and conducting it from said 60 cells, for the purposes specified.

8. A carbureter comprising a suitable compartment, curtains therein dividing the same into continuous passage-ways which circulate from the outer wall of said compartment about the center thereof, absorbent partitions longitudinally disposed between said curtains, and means for introducing atmosphere at one end of said passage-way formed by said curtains and discharging atmosphere at 70 the other end thereof.

9. A carbureter, comprising a plurality of superposed compartments, curtains 7, 8 and 9, by which each compartment is divided into a series of circulating-cells 10, 11 and 12, the curtain 7 hanging lower than the curtains 8 and 9, a tube 17, which projects above the surface of the hydrocarbon oil in each compartment, a branch tube 19, depending into the oil, an opening near the floor of each compartment, an air-supply tube, which connects with said cells in the lower compartment, an outlet for the carbureted air from the upper compartment, a supply-tank above said compartments, a tube connecting said supply-tank with the upper compartment, a valve in said tube, a chamber 41 adjoining said compartments and in communication with the lower compartment, a float in said chamber, a connection between said float and valve, 85 and a second valve-controlled opening for drawing off the refuse and heavier substances in the oil. 90

In testimony whereof I have signed my name to this specification in the presence of 100 two subscribing witnesses.
